MASSAGE VIBRATOR

David B. Brown, Bellingham, Wash.; Betsy O. Brown, executrix of said David B. Brown, deceased

Application May 16, 1952, Serial No. 288,157

3 Claims. (Cl. 128—49)

1

This invention relates to massaging devices and more particularly to a motor driven massage vibrator especially useful for massaging the scalp.

It is among the objects of the invention to provide an improved massage vibrator which can be easily held in one hand of an operator and applied to the body of a patient or customer; which is especially adapted for use by barbers or hairdressers to massage the scalps of customers in barber shops and similar places of business; which is motor driven and has oppositely moving massaging pads so that the device does not tend to be self-propelled; which subjects the body portion to which it is applied to a strong and positive rubbing and vibrating action; which has pivotally mounted massaging pads which are adjustable to the contour of the body part to which they are applied; and which is simple and durable in construction, economical to manufacture, easy to use, and positive and effective in operation.

Other objects and advantages will become apparent from a consideration of the following description and the appended claims in conjunction with the accompanying drawings wherein:

Figure 1 is a bottom plan view of an electric massage vibrator illustrative of the invention;

Figure 2 is a front end elevational view of the device illustrated in Figure 1;

Figure 3 is a longitudinal cross sectional view on the line 3—3 of Figure 1;

Figure 4 is a longitudinal cross sectional view on the line 4—4 of Figure 3;

Figure 5 is a front elevational view of the device similar to Figure 2 but with the casing enclosing the mechanism of the device removed;

Figure 6 is a perspective view of a lever arm constituting an operative component of the device; and

Figure 7 is a fragmentary cross sectional view on the line 7—7 of Figure 2.

With continued reference to the drawing, the device comprises an electric motor, generally indicated at 10, having a housing 11 of elongated, cylindrical shape, a motor shaft 12 projecting coaxially from one end of the housing, a motor controlling switch 13 mounted on the other end of the housing and an extension cord 14 leading into the housing adjacent the switch 13.

A sheet metal casing 15 is mounted on the motor 10 and includes a clamp portion 16 of cylindrical shape longitudinally split and provided with spaced apart, longitudinally extending flanges 17 and 18 at respectively opposite sides

of the split or opening therein and a portion 19 extending longitudinally from the end of the motor housing 11 from which the shaft 12 projects and providing spaced apart and substantially parallel side walls 20 and 21 and a partly cylindrical intermediate portion 22 joining the side walls at the normally upper side of the device.

The motor housing is received in the clamp 10 portion 16 of the casing 15 and the clamp is secured around the motor housing by clamp screws 23 and 24 extending through registering apertures in the flanges 17 and 18.

A pair of bearing bars 25 and 26 are disposed 15 between the flat side walls 20 and 21 of the casing in spaced apart and substantially parallel relationship to each other and are substantially parallel to and spaced from the motor shaft 12.

Screws 27 and 28 disposed substantially perpendicular to the bars 25 and 26 at the respective 20 opposite ends of the pair of bars extend through registering apertures in the side walls 20 and 21 of the casing and in the bars 25 and 26. Spacing sleeves 29 and 30 surround the screw 25 between the side walls 20 and 21 respectively 25 of the casing and the bars 25 and 26 and nuts 31 and 32 are threaded onto the screws at the sides of the bars 25 and 26 remote from the spacing sleeves 29 and 30 to hold the ends of the bars firmly against the adjacent ends of the spacing sleeves.

Similar spacing sleeves 33 and 34 surround the screw 28 between the casing side walls 20 and 21 and the bars 25 and 26 and nuts 35 and 36 are threaded onto the screw 28 and bear 35 against the sides of the bars 25 and 26 respectively remote from the spacing sleeves 33 and 34 to hold the corresponding ends of the bars firmly against the spacing sleeves.

The screws 27 and 28 and the associated spacing sleeves and nuts firmly support the bearing bars 25 and 26 in the casing 15 and in fixed position relative to the motor 10 and motor shaft 12.

The bars 25 and 26 are each provided with an aperture adjacent the midlength location thereof and these apertures are in alignment with each other transversely of the casing 15. A shaft 38 extends through and is journaled in the apertures in the bearing bars 25 and 26 and a worm wheel 40 is mounted on the shaft 38 between the bars 25 and 26. A worm 41 on the motor shaft 12 meshes with the worm gear 40 to drive the worm gear and the shaft 38 and eccentric cams 55 42 and 43 are mounted on the cam shaft 38 one

at each end thereof and at the inner sides of the side walls 21 and 21 respectively of the casing 15. These eccentric cams are disposed substantially one hundred and eighty degrees out of phase with each other for a purpose which will presently appear.

U-shaped levers 45 and 46 are disposed at respectively opposite sides of the motor shaft 12 and extend through the casing 15 so that one arm 47 of the lever 45 is disposed between the casing side wall 20 and the bearing bar 25 and one arm 48 of the lever 46 is disposed between the casing side wall 21 and the bearing bar 26. The other arm 49 of the lever 45 is disposed at the outer side of the casing side wall 20 and the other arm 50 of the lever 46 is disposed at the outer side of the casing side wall 21, the two arms of each lever being spaced apart and substantially parallel to each other.

Elongated lugs 51 and 52 are secured to the bearing bars 25 and 26 respectively and extend substantially perpendicular from these bars past the motor shaft 12, one at each side of the latter. Pivot pins 53 and 54 are mounted each at one end in the lugs 51 and 52 respectively near the ends of these lugs remote from the bearing bars 25 and 26 and project from the corresponding lugs outwardly through openings provided in the casing 15. The levers 45 and 46 are pivotally mounted on the pins 53 and 54 respectively for oscillating movement about a common axis disposed substantially in a plane which includes the rotational axis of the shaft 38 and is perpendicular to the rotational axis of the motor shaft 12.

A bifurcated cam follower 55 is mounted on the arm 47 of the lever 45 and receives the eccentric cam 42 and a similar bifurcated cam follower 56 is mounted on the lever arm 48 and receives the eccentric cam 43 so that the levers are rocked in respectively opposite directions about the axes provided by the pivot pins 53 and 54 when the shaft 38 is driven by the motor and rotates the eccentric cams 42 and 43.

The outer arms 49 and 50 of the levers 45 and 46 are in the form of flat bars detachably connected to the intermediate portions of the levers by suitable releasable connections, as indicated at 57 and 58, and these arms extend from the intermediate portions of the levers past the side of the worm gear 40 remote from the worm 41.

At their ends remote from the pivot pins 53 and 54 the lever arms 49 and 50 are provided with ears, as indicated at 60 and 61 for the arm 49 and 62 and 63 for the arm 50, which ears extend longitudinally of the corresponding lever arms at the outer or distal ends of the latter and perpendicularly from each arm toward the opposite arm in spaced apart and substantially parallel relationship to each other.

A U-shaped bracket 65 is disposed between the ears 60 and 61 on the lever arm 49 and is pivotally connected to these ears by a pivot pin 66 extending through registering apertures in the ears 60 and 61 and in the bracket legs and a similar U-shaped bracket 67 is disposed between the ears 62 and 63 of the lever arm 50 and pivotally connected to these ears by a pivot pin 68 which extends through registering apertures in the ears 62 and 63 and in the bracket legs.

Massaging pads 70 and 71 formed of a flexible, resilient material, such as vulcanized rubber, are mounted on the brackets 65 and 67 respectively and are rockable about axes provided by the pivot pins 66 and 68 which axes are spaced inwardly from the corresponding lever arms 49 and 50 and

disposed substantially at right angles to the longitudinal center lines of these lever arms and substantially parallel to the bearing bars 25 and 26 so that the pads can rock toward and away from each other to adjust themselves in accordance with the contour of a body portion to which they are applied.

Each of the pads 70 and 71 comprises a solid base portion 72 of circular shape and a plurality of conical projections or peaks 73 extending from the side of the base portion remote from the associated bracket 65 or 67 in side by side relationship to each other.

When the device is in operation the two massaging pads 70 and 71 are moved forwardly and backwardly longitudinally of the motor 10 but in respectively opposite directions so that when one of the pads is moving forwardly the other is moving backwardly or rearwardly relative to the motor. This prevents any tendency for self-propulsion of the device and the device will move over a body part to which it is applied only as it is moved by the operator holding the device.

The motor 10 is a fractional horse-power motor of small size and light weight and the mechanism connecting the motor to the massaging pads and the casing enclosing this mechanism are also of small size and light weight so that the device can be easily held in one hand of the operator while being used to massage the scalp of a customer.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A massage vibrator comprising an electric motor having a housing of substantially cylindrical shape and a rotatable shaft projecting from one end of said housing, a casing mounted on said motor housing and including spaced apart side walls extending longitudinally from said one end of the housing, bearing bars disposed between said casing side walls and having aligned apertures one in each bar, means supporting said bars on the side walls of said casing in spaced apart and substantially parallel relationship to each other, a shaft extending through and journaled in the apertures in said bearing bars in transverse and spaced relationship to said motor shaft, a worm gear mounted on said shaft between said bars, a worm on said motor shaft meshing with said worm gear to drive the latter, eccentric cams mounted on said shaft one at each end thereof at the outer sides of said bearing bars and disposed out of phase with each other, U-shaped levers extending through said casing and disposed one at each side of said pair of bars and each having one arm disposed within and one arm outside of said casing, bifurcated cam followers secured one to each lever arm disposed within said casing and receiving the corresponding eccentric cams, means pivotally supporting said levers from said bearing bars for oscillating movement of said levers about a common axis spaced from and substantially parallel to the rotational axis of said shaft, massaging pads disposed one adjacent each lever arm outside of said casing at the ends of said arms re-

move from said means pivotally mounting said levers on said bearing bars, and means pivotally connecting said pads to the corresponding lever arms for rocking movement about axes disposed substantially perpendicular to the longitudinal center lines of the corresponding lever arms and substantially parallel to said bearing bars.

2. A massage vibrator comprising a motor having an elongated housing constituting a handle for the vibrator and a motor shaft extending longitudinally from one end of said housing, a hollow casing mounted on said one end of said housing and receiving said motor shaft, bearing structures in said casing spaced from respectively opposite sides of said motor shaft, a cam shaft journalled in said bearing structures with its rotational axis spaced from and at right angles to the rotational axis of said motor shaft, levers disposed in said casing one adjacent each of said bearing structures and extending out of a side of said casing spaced from and substantially parallel to the rotational axis of said motor shaft, means pivotally mounting said levers in said casing for rocking movements about a common axis parallel to the rotational axis of said cam shaft and spaced from the side of said cam shaft remote from the side of said casing from which said levers extend, eccentric cams mounted on said cam shaft one adjacent each of said bearing structures substantially 180 degrees out of phase with each other and connected to the corresponding levers to impart to said levers oppositely directed rocking movements in spaced apart planes parallel to each other and to the rotational axis of said motor shaft, massage pads mounted one on each of said levers at the ends of said levers extending out of said casing, and speed reducing means drivingly connecting said motor shaft to said cam shaft.

3. A massage vibrator comprising a motor having an elongated housing constituting a handle for the vibrator and a motor shaft extending

longitudinally from one end of said housing, a hollow casing mounted on said one end of said housing and receiving said motor shaft, bearing structures in said casing spaced from respectively opposite sides of said motor shaft, a cam shaft journalled in said bearing structures with its rotational axis spaced from and at right angles to the rotational axis of said motor shaft, levers disposed in said casing one adjacent each of said bearing structures and extending out of a side of said casing spaced from and substantially parallel to the rotational axis of said motor shaft, means pivotally mounting said levers in said casing for rocking movements about a common axis parallel to the rotational axis of said cam shaft and spaced from the side of said cam shaft remote from the side of said casing from which said levers extend, eccentric cams mounted on said cam shaft one adjacent each of said bearing structures and disposed substantially 180 degrees out of phase with each other and connected to the corresponding levers to impart to said levers oppositely directed rocking movements in spaced apart planes parallel to each other and to the rotational axis of said motor shaft, massage pads mounted one on each of said levers at the ends of said levers extending out of said casing, a worm gear on said cam shaft between said bearing structures, and a worm on said motor shaft meshing with said worm gear and drivingly connecting said motor shaft to said cam shaft.
